UNITED STATES PATENT OFFICE

WILLIAM MACDONALD AND HUGH MACDONALD, OF INVERNESS, SCOTLAND

APPLIANCE FOR USE IN HAIR WAVING

Application filed August 25, 1931, Serial No. 559,305, and in Great Britain August 30, 1930.

This invention relates to apparatus for use in hair-waving appliances of the type wherein steam is injected into tubes or jackets thereby subjecting the hair, which has been 5 previously wound onto curlers and placed inside of the jackets, to a moist heat and steam treatment.

The invention is more particularly concerned with apparatus of the above type in which a plurality of steam boilers is provided, one for each hair waving appliance, and an object of the present invention is to provide an improved supporting device for the boilers whereby filling of the boiler is facilitated 15 and in a manner which avoids spilling or overflowing of the water.

According to the invention the support for a series of boilers of the type referred to comprises a tray or container which is provided with a gutter or the like for collecting overflow of water or the like and carrying it to waste.

Further features of the invention will be hereinafter described and defined in the 25 claims.

In the accompanying drawings—

Figure 1 is an elevation partly in section of a supporting tray according to the invention.

Figure 2 is a half plan of the tray or container.

The invention will be described in connection with steam boilers as shown and claimed in our British patent application No. 25,987 of 1930.

The boilers (only one of which is shown) 3 are arranged in a circular series and are provided with a valve device 4, a heater 5, a down-take connection 6, a filling aperture 7 and a safety valve connection 8.

In carrying the invention into effect a boiler supporting tray or container 9 is provided which is carried by a hollow standard 10 having telescoping tubes whereby the height 45 may be adjusted, the lower tube 11 having feet 12 provided with casters.

The tray may be of any suitable shape in plan, and in the form shown is circular, the boilers being arranged adjacent the circumferential wall 13. An annular gutter or

drain 14 is provided which is connected with a down-take tube 15, the lower end of which projects into the standard 10, whereby any liquid collecting in the gutter is led away to a waste vessel 16 suitably clipped to the 55 feet 12.

The gutter 14 may be of any suitable shape in cross-section, square, semicircular or the like, and is preferably located below the ring of boilers, but may be arranged in any other 60 suitable position.

As an alternative to the annular gutter 14 the base of the container may be dished or otherwise formed so that liquid will collect and be drained away.

It will be appreciated that when filling the boilers by the filling aperture 7 any water overflowing will be collected by the gutter and drained away to the vessel 16 which may be removed from time to time and emptied. 70 Similarly, any water of condensation resulting from steam escaping from the boilers when first boiling up with open valve will be collected and carried away.

The base and wall of the tray are provided with apertures 17 and 18 respectively to accommodate the downtake tube 6 and valve 4. The holes 18 may be replaced by upwardly extending slots but it is preferred that the rim 19 shall be complete for the purpose 80 of making the wall 13 rigid.

The tray is connected to the standard 10 by a nut 20 and screwed cap 21 which latter is threaded to receive a bolt 22, adapted to hold a cover plate 23 in position.

The cover plate is provided with a circumferential series of apertures 24 coinciding with the safety valve connections 8.

Preferably, the bolt 22 is bored to receive a pin 25 by which a filling tank 26 may be supported. The filling tank is provided with a suitable flexible connection 27 and valved nozzle (not shown) for filling the boilers.

According to a modified form the capacity of the gutter may be such that the tube 15 is unnecessary and in such case a valved connection may be provided on the gutter by which the collected water or moisture may be drained from time to time.

With the form of boiler as described in our 104

companion application in which the valve 4 is actuated by a longitudinally adjustable rod 4^a it may happen that a slight escape of water, in the nature of a drop or two, occurs when the rod 4^a is moved outwardly. In order to catch such drops a drip tray 28 is provided of annular form which may be secured to the periphery of the base of the container 9 in any suitable manner such as by screw bolts and nuts.

The drip tray 28 may be utilized for carrying the usual supporting devices for the steam conveying pipes to the curling means.

We claim:

15 1. A supporting tray or container for a series of steam boilers for use in connection with hair-waving appliances, wherein means are provided below the normal level of the tray for collecting or draining away water 80 overflowing from the boilers, or other moisture.

25 2. A supporting tray or container for a series of steam boilers for use in connection with hair-waving appliances, comprising an annular gutter in the base of the tray and a connection from such gutter to waste. 85

30 3. A tray for a series of steam boilers for use in connection with hair-waving appliances, a hollow standard for supporting the tray, an annular gutter in the base of the tray for collecting water overflowing from the boilers, or other moisture, and a pipe opening into the gutter and extending into the hollow standard. 90

35 4. A tray for a series of boilers as claimed in claim 3 wherein a removable waste vessel is mounted at the lower end of the supporting standard. 100

40 5. A supporting tray for a series of steam boilers for use in connection with hair-waving appliances, having a surrounding wall, an annular gutter in the base of the tray and a connection from the gutter to waste, and apertures in the wall and base for accommodating valve operating means and downflow tubes of the boilers. 105

45 6. A boiler supporting tray as claimed in claim 5 wherein a cover plate is provided having apertures for accommodating safety valve connections in the boilers. 110

55 7. A boiler supporting tray as claimed in claim 5 wherein a cover plate is provided, a fastening bolt for securing the plate in position, said bolt having a recess to accommodate a pin adapted to support a vessel for filling the boilers. 115

60 8. A tray as claimed in claim 3 having a surrounding wall, apertures in the base and wall for accommodating downflow pipes and valve connections in the boilers, a cover plate adapted to rest on the boilers and having apertures accommodating safety valve connections in the boilers, a bolt for securing the 120 cover plate in position, said bolt being bored 125

to receive a pin adapted to support a vessel for filling the boilers.

9. A supporting tray as claimed in claim 5, having a drip tray extending beyond the surrounding wall, for the purposes described. 70

In testimony whereof we have signed our names to this specification.

WILLIAM MacDONALD.
HUGH MacDONALD.
